United States Patent Office

Des. 221,636

Patented Aug. 31, 1971

221,636

PALLET

John Edward Moses, Bricket Wood, England, assignor to John Dale Limited, London, England

Filed Aug. 11, 1970, Ser. No. 24,415

Term of patent 14 years

Claims priority, application Great Britain Feb. 16, 1970

Int. Cl. D12—14

U.S. Cl. D14—3

FIG. 3.

FIG. 4.

FIG. 1 is a perspective view from above and one side of the pallet showing my new design;

FIG. 2 is a perspective view from below and the other side thereof,

FIG. 3 is an underplan view thereof, and

FIG. 4 is a side view of the pallet.

The two sides not shown are the same in appearance as the sides shown in FIGS. 1 and 2.

I claim:

The ornamental design for a pallet, substantially as shown and described.
